UNITED STATES PATENT OFFICE

WILLIAM G. BOSWORTH, OF NEW YORK, N. Y.

OPENING AND SEALING DEVICE FOR CARTONS

Application filed June 29, 1927. Serial No. 202,169.

This invention relates to an improvement in carton opening and sealing devices, that is to say, to devices which may be employed for providing an opening or aperture in cartons such as cartons of cereals, coffee, and the like, my device being so constructed and arranged that after the carton has been opened, the same may be kept sealed by the device itself by leaving the same in place thereon.

One of the objects of my invention is the provision of a device of the character indicated which is simple in construction, inexpensive to manufacture, and at the same time very effective in operation.

A further object of my invention is the provision of a device of the character indicated, in which means are provided for cutting or removing a section of one wall of a carton, so as to enable portions of the contents of the carton to be removed from time to time, the device being so constructed, however, as to provide a seal for the opening thus provided when the contents of the carton are not being removed.

In the accompanying drawings, wherein embodiments of my invention have been illustrated,

Fig. 1 is a view in perspective of my device in place on a carton;

Fig. 2 is a section on the line 2—2 of Fig. 1;

Fig. 3 is a plan view of the device from beneath the same;

Fig. 4 is an elevational view of the opening and closing device;

Fig. 5 is a sectional elevational view of a modified form of my invention;

Fig. 6 is a plan view thereof; and

Fig. 7 is a view taken on the line 7—7 of Fig. 5.

Referring to the drawings in detail and first of all to Figs. 1 to 4 inclusive, 1 designates a carton of cardboard or a similar material. The desideratum is to provide a device by which this carton may be opened by

removing a section of a wall thereof, as, for example, by the removal of a section of the top, designated 2, the device employed for this purpose being of such a character as to serve as a seal for the opening thereby provided when the contents of the carton are not being removed.

The device consists of an upper member 3 and a lower member 4, joined at their rear ends by a web 5, which is an integral part of the members 3 and 4. In other words, the metal composing the upper member 3 and the lower member 4 is bent over, so that the two members 3 and 4 will be positioned rigidly in superimposed spaced relation, as plainly indicated in Fig. 2. The upper member 3 preferably extends beyond the extreme end of the lower member 4, as shown in Figs. 2 and 3. The advance edge of the lower member 4, as indicated in the drawings, is bent downwardly and shaped to provide a knife or knife edge 6. By bending the member 4 downwardly, I am assured that the advance edge thereof will enter beneath the face of the lowermost member comprising the carton top. Both members 3 and 4 are provided with an orifice, the orifice in the member 3 which is illustrated as circular being designated 7 while that in the member 4 is designated 8. In providing the orifice 7 in the member 3, the metal of this member is drawn upwardly to provide an upwardly extending guiding flange 9 surrounding the orifice 7, this flange projecting a short distance out of the plane of the upper face of the member 3. The two orifices 7 and 8 are in register with each other. The distance between the members 3 and 4 may be varied in making up the device, to suit different conditions, but in all cases they must be separated sufficiently to enable the material of the top 2 of the carton to be inserted between these two members, as shown in Fig. 2.

The upper member 3 has a portion 10 struck out of the same and bent downwardly, so

as viewed in Fig. 1, so as in effect to form a continuation of the connecting web 5. This struck out portion 10 extends well below the lower member 4 and its function will be pointed out hereinafter. The lower plate or member 4 is also provided with shoulders or abutments 11 struck out of the metal of the plate, these abutments or shoulders being bent downwardly out of the plane of the 10 under side of the plate.

The orifices 7 and 8 receive a cylindrical opening and sealing member 12, open at its lower end, this open lower end of the member being shaped to provide a circular knife 13. The knife 13 may be provided with any suitable number of blades, two having been indicated, as I have found this number satisfactory. The upper end of the cylindrical member 12 carries and has attached to it a 15 plate 14. In the manufacture of the cylindrical member 12, the material of the plate 14 is shaped so as to provide two integral ears or lugs 15 at opposite sides of the member 12, these ears providing a convenient means 20 for manually rotating the member.

Secured to the closed end 14 of the cylindrical member 12 and disposed centrally thereof is a pointed member 16 extending longitudinally of the member 12 and provided with a shoulder 17 adjacent its pointed 25 end, the member projecting beyond the end of the member 12 until the shoulder 17 is slightly beyond the lower end of the knives 13.

30 The operation of my improved device is as follows:

The unit composing the upper and lower members or plates 3 and 4 is pressed against the side wall of the carton at any desired 35 location, with the upper plate or member 3 resting upon the top 2. It will be understood, of course, that the cylindrical member 12 is at that time not in place on the device. By a slight pressure the sharpened 40 edge 6 of the lower member 4 will be caused to enter the side wall of the carton, permitting the plate 4 to be pushed into the carton beneath the top 2, with the upper plate 3 overlying this top 2. The device is pushed 45 inwardly until it occupies substantially the position shown in Fig. 2, at which time, it will be seen, the web 5 and struck out portion 10 of the lower plate 4 will abut or contact with the side wall 18 of the carton. At the 50 same time the shoulders or abutments 11 on the plate 4 will have been pushed inwardly with respect to the carton sufficiently to bring the free ends of these shoulders into contact with the inner face of the side wall 18 of the carton, the shoulders, as will now 55 be appreciated, preventing easy withdrawal of the plates 3 and 4 from the carton. It will be seen also at this time that the web 5 and struck out portion 10 of the plate 4 have 60 a relatively long bearing surface against the

side wall 18 of the carton, thereby to prevent twisting of the plates 3 and 4 with respect to the carton and preventing bulging of the end or side of the carton. The web 5 also provides a seal for the slit or slot made in the carton when the plate 4 is inserted.

The cylindrical member 12 is next inserted in the orifice 7 in the upper plate 3, being guided by the guiding flange 9, and as this cylindrical opening and sealing member is pushed downwardly, but before the knives 13 have begun to function, the pointed member 16 will pass downwardly through the orifice 8 in the lower plate 4 having passed through the material 2 at the point where a section of this material is to be removed. As above noted, the shoulder 17 on the member 16 is projected beyond the end of the knives 13, so that before the knives have finished their cutting operation the member 16 will have penetrated the material 2 to the point where the shoulder 17 is at the under side of the material. The cylindrical opening and sealing member 12 may then be rotated manually by means of the ears or lugs 15, a slight pressure being brought to bear on the member at the same time, so as to cause the knives 13 to cut the material 2, the member 12 being forced downwardly until a section 19 has been completely cut out of the carton top. Inasmuch as the member 12 and knives 13 are circular, the cut out portion 19 will be in the form of a circular disk, and this disk at this time will be impaled upon the sharpened member 16. The member 12 may then be 100 lifted out of the plates 3 and 4 gradually, carrying with it the disk 19. The contents of the carton or so much of the contents as desired may then be discharged through the opening in the top 2 provided by the removal of the disk 19. Inasmuch as the opening left by the removal of the disk 19 was made by the knives 13, it will be obvious that by merely replacing the cylindrical member 12 in place again the carton will once more be 105 sealed. It will be seen also that the lower member 4 provides a support for the material of the carton out of which the disc 19 is to be cut preventing movement of the same downward during the piercing of the material by the sharpened member 16 as well as during the operation of cutting the disc 19 out of the material, thereby insuring that every thickness of the carton which is usually 110 two or three layers thick will be cut through. 115

The construction above described therefore provides means for opening a carton and for sealing the same thereafter, the means employed being extremely simple in construction and operation and at the same time effective. It will be seen also that by providing the web 5 and struck out portion 10 of upper plate 3, accidental displacement of the device with respect to the carton is prevented in a very simple manner, thereby permitting 120 125 130

the member 12 at all times to be readily placed in position to seal the carton.

I have referred to the plates 3 and 4 of my improved device as upper and lower plates, respectively; I have also referred to the portion 2 of the carton as the top of the carton, and the portion 18 as the side thereof. It is to be understood, however, that these expressions have been used merely for clarity of description and are not intended by way of limitation.

In the form of my invention as illustrated in Figs. 5, 6 and 7 I have modified somewhat the construction above described. In this instance, while the upper member 3 and lower member 4 are joined by a web 5, the struck out portion 10 of the form above described has been omitted, and in place thereof I weld or otherwise rigidly secure a depending flange 20 to the rear face of the web 5, this depending flange extending across the entire width of the plates 3 and 4. The purpose of this construction, as distinguished from the struck out portion 10 of the first form, above described, is to provide a longer bearing surface than is possible with the struck out portion 10. The flange 9 with which the upper plate 3 is provided is spun or bent over at the upper end thereof, as plainly indicated at 21. The cylindrical opening and sealing member 12' in this instance is formed at its upper end with a lateral extension 22, and opposite this extension with another lateral extension 23. The extension 22 provides one member of a hinge for a cover or lid 24, which lid or cover is provided with a flange 25, this flange 25 and the flange 22 on the member 12' being hinged to each other by a pin 26. The lateral extension 23 on the member 12', and which is preferably diametrically opposite the hinge just described, is bent downwardly and inwardly, as plainly indicated in Fig. 5, the inwardly extending portion 27 thereof being adapted to engage the flange 21 on the member 9, so that when the member 12' in this form of my invention is inserted in place in the members 3 and 4, the portion 27 of the extension will engage the bent over portion 21 of the flange 9 on the upper plate 3. The bent over portion 23 is of a resilient nature, however, so that by a slight effort the member 12' may be completely removed from the orifices 7 and 8.

Attached to the cover or lid 24 is a sharpened member 28 the function of which is the same as that of the member 16 already referred to, but by reason of the fact that the member 28 is pushed through the material 2 of the carton with a swinging motion about the hinge pin 26 rather than by a straight downward thrust, the end of the member 22 is in the form of a knife 29, the advance or cutting edge of which is designated 30. This member 28, however, as in the case of the member 16, is provided with a shoulder 31,

and when the cover or lid 24 is in closed position this shoulder projects beyond the lower end of the knives 13'. The operation of this device when in use is similar to the device of Fig. 1, and hence will not be described in any detail.

The flange 9, referred to above and which functions as a guiding flange, also provides a spout for facilitating discharge of the contents of the carton.

I have mentioned also that the pointed members 16 and 28 are secured to the upper end of the opening and sealing member 12 or 12', respectively, but it is to be understood that these members may be attached to some other part of this member, as long as its point is disposed centrally thereof. While I have illustrated and described my device as comprising a lower member 4 provided with an orifice designated 8, it is to be understood that this member may be substituted by a forked member, for example, the forks being sufficiently spaced to permit of the passage of the cylindrical member 12 therebetween.

It will be obvious that various modifications may be made in the construction above described within the purview of this invention.

What I claim is:

1. In a container opening and sealing device, the combination of an upper member and a lower member arranged in superposed and spaced relation, each of said members being provided with an orifice, said orifices registering with each other, said lower member adjacent the rear end thereof being provided with lugs or shoulders extending away from the upper member and out of the plane of the lower member to engage the inner face of a container wall to prevent withdrawal of said members from the container, a sealing member received by the orifices in said members, said sealing member being rotatable and provided at its lower end with a knife for cutting material inserted between the two members, and a pointed member carried by said sealing member and extending beyond the end of the knife with which the sealing member is provided, for piercing the material to be cut in advance of the cutting operation.

2. In a device of the class described, the combination of an upper and a lower member rigid with respect to each other, the advance end of said lower member being provided with a knife edge, said members being arranged in superimposed and spaced relation and each being provided with a circular orifice, said orifices registering with each other, a cylindrical sealing member received by said orifices and rotatable with respect to said members, a knife at the lower end of said sealing member, and a pointed member carried by said sealing member and

extending beyond the knife of the sealing member, so as to pierce the material to be cut out by the knife in advance of the complete cutting operation.

- 5 3. In a device of the class described, the combination of an upper and a lower member arranged in spaced superimposed fixed relation to each other and adapted to receive between them material to be cut, each of said 10 members being provided with a circular orifice, said orifices registering with each other, a cylindrical sealing member closed at its upper end and adapted to be rotated in said orifices, a knife at the lower end of the sealing member operable when the sealing member is rotated to remove that portion of the material to be cut lying between said orifices, and a pointed member carried by the closed end of said cylindrical member and extending lengthwise of the cylindrical member to a point beyond the end of the knife of the sealing member, to pierce the material to be removed prior to its severance by the knife of the sealing member.
- 15 4. In a device of the class described, the combination of an upper and a lower member arranged in spaced superimposed relation, a web joining the two members at one end thereof in such manner that the material 20 to be cut or removed from a carton to which the device is to be attached will lie between the members, each of said members being provided with a circular orifice, said orifices registering with each other, a cutting and 25 sealing cylindrical member received by said orifices and rotatable relatively to said members, a closure for the upper end of said cylindrical member, a knife at the lower end thereof, and a pointed member having a 30 shoulder formed thereon carried by said cylindrical member, said pointed member projecting beyond the lower end of the cylindrical member sufficiently to advance the shoulder thereof beyond said knife.
- 35 5. In a device of the class described, the combination of an upper and a lower member arranged in rigid superimposed spaced relation and provided with orifices in register with each other for the insertion of a puncturing instrument, a web joining one end of 40 said members and extending below the lower face of the lower member, and a knife formed at the other end of said lower member for the purpose set forth.
- 45 6. In a device of the class described, the combination of an upper and a lower member arranged in rigid spaced superimposed relation and provided with orifices in register with each other for the insertion of a puncturing instrument, the lower member being provided with an advance or leading cutting edge, a web joining one end of said members and extending below the lower face of the 50 lower member for the purpose set forth, and lugs or shoulders on the lower face of the

lower member and extending downwardly out of the plane thereof.

7. In a device of the class described, the combination of an upper and a lower member arranged in rigid spaced superimposed relation and provided with orifices in register with each other for the insertion of a puncturing instrument, shoulders or abutments struck out of said lower member and bent downwardly away from the upper member, 70 said shoulders or abutments being spaced slightly from the rear ends of said members, the said lower member being provided with a leading or advance cutting edge.

8. In a device of the class described, the combination of an upper member and a lower member joined to each other rigidly in spaced superimposed relation, each of said members being provided with orifices, said orifices registering with each other for the insertion of a 85 puncturing instrument, the advance or leading edge of the upper member extending beyond the leading cutting edge with which the lower member is provided, and abutments or shoulders struck out of the lower member extending downwardly out of the plane thereof, 90 said shoulders terminating short of the rear end of the lower member.

9. In a device of the class described, the combination of an upper member and a lower member arranged in spaced rigid superimposed relation, each of said members being provided with a circular orifice, said orifices registering with each other, the upper face of the upper member being provided with an 100 upstanding guiding flange surrounding the orifice in said upper member, the advance edge of the lower member being provided with a knife edge for the purpose set forth, and shoulders or abutments struck out of the 105 lower member adjacent the rear end thereof, said shoulders extending downwardly out of the plane of the lower face of the lower member.

10. In a device of the class described, the combination of an upper and a lower member, arranged in superposed relation, and provided with registering orifices for the insertion of a puncturing instrument, means for joining the two members to each other, the forward end of the upper member projecting beyond the forward edge of the lower member, the forward edge of the lower member being bent downwardly out of the plane of the lower face thereof and provided with a 110 knife edge.

11. In a device of the class described, a hollow cylindrical sealing member permanently closed at its upper end, a circular knife integral with said member and disposed at 125 the lower end thereof, a pointed member rigidly secured to the cylindrical member with its point disposed in line with the axis of the cylindrical member, said pointed member extending lengthwise of said cylindrical sealing 130

member to a point beyond the edge of said knife whereby in applying the cylindrical member to a carton the pointed member will pierce the carton in advance of the functioning of the circular knife, and a shoulder on said pointed member positioned beyond the lower or advance edge of the knife in such position as to enter the carton before the circular knife functions whereby the section of the carton removed by the knife will be held to the pointed member.

This specification signed this 25th day of June, 1927.
